Arthur A. Tobias, Chicago, Ill., assignor to Raymond T. Moloney, Chicago, Ill.

Application April 28, 1945, Serial No. 119,294

Term of patent 14 years

(Cl. D37—1)

To all whom it may concern:

Be it known that I, Arthur A. Tobias, a citizen of the United States and a resident of Chicago, Cook County, Illinois, have invented a new, original, and ornamental Design for a Spiral Grinding Fixture, of which the following is a specification, reference being had to the accompanying drawing, forming part thereof.

Fig. 1 is a perspective view of a spiral grinding fixture embodying my new design;

Fig. 2 is a side elevational view of the same;

Fig. 3 is a top plan view of the same.

I claim:

The ornamental design for a spiral grinding fixture, as shown.

ARTHUR A. TOBIAS.
